DUSTPAN MECHANISM

Norman W. Cummins, Louisville, Ky.

Application June 30, 1938, Serial No. 216,688

10 Claims. (Cl. 15—41)

My invention relates to improvements in carpet sweeper constructions, and particularly to improvements in the construction and arrangement of dustpan operating mechanisms.

The features of my invention as disclosed in this application, have particular reference to carpet sweepers of the class that do not employ a conventional exterior bail for pivotally attaching the operating handle to the casing. In sweepers of this class, the operating handle may be pivotally mounted on the top of the sweeper casing, or projected through an opening in the top of the sweeper casing and secured to a transverse shaft within the casing, which shaft is pivotally mounted on the end partitions of the casing. Other equivalent methods of pivotally attaching the operating handle to the sweeper casing will be apparent as the present disclosure is studied by those familiar with carpet sweeper constructions. However, it is to be understood that, although the present disclosure is made in specific terms of an interiorly pivoted handle without an external bail, the scope of my invention is in no wise to be limited other than by the scope of the appended claims. It is to be further understood that the scope of this disclosure, and its appended claims, is not to be lessened or restricted by reason of the filing of my copending application Serial Number 216,687, filed June 30, 1938, and entitled "Carpet sweeper," which application embraces certain specific problems encountered in applying the broad principles of this invention to sweepers of the class that employ an external bail for pivotally attaching the operating handle to the sweeper casing.

The principal object of this invention is to provide a construction whereby the actuating mechanism for opening and closing the dustpans may be placed on the operating handle of a carpet sweeper. Thus, my invention has for its object the placing of the dustpan actuating member in an accessible and convenient location.

A further object of my invention is to provide a dustpan operating mechanism that is easily operated, and positive in its action.

A still further object of my invention is to provide a relatively simple, practical and efficient construction that will facilitate assembly and reduce manufacturing costs.

The advantages of these and other objects of my invention will be more apparent as the following description is read in connection with the accompanying drawings illustrating one preferred embodiment of the broad principles of my invention and its constructional details, in which:

Figure 1 is a plan view of a sweeper embodying my invention, showing the general relation between the operating handle 4 and the top of the sweeper casing, when the operating handle is substantially in a vertical position;

Figure 2 is an end view of the sweeper illustrated in Figure 1, showing the relation between wheels 15, brush 14, dustpans 18, 18, retaining spring 16 and operating handle 4, when the operating handle is substantially in a vertical position;

Figure 3 is an enlarged partial sectional view taken along lines 3—3 of Figure 2, illustrating the construction and arrangement of the dustpan actuating lever 3 in terms of the operating handle 4;

Figure 4 is an enlarged partial sectional view taken along lines 4—4 of Figure 2, illustrating the manner in which spring lever 11 is pivotally mounted on the end partition 12;

Figure 5 is an enlarged partial sectional view taken along lines 5—5 of Figure 3, illustrating the construction and arrangement of the pivot 2a for the dustpan actuating lever 3;

Figure 6 is a partial sectional view taken along the transverse center line of Figure 1, illustrating the manner in which chain 8, or its equivalent, interconnects the actuating plunger 7 and spring lever 11;

Figure 7 is an enlarged partial sectional view taken along lines 7—7 of Figure 6, illustrating the method of attaching the flared spring guide 21 to the hollow transverse shaft 10;

Figure 8 is an enlarged partial sectional view taken along lines 8—8 of Figure 6, showing the construction of the hollow shaft 10;

Figure 9 is an enlarged partial sectional view taken along lines 9—9 of Figure 2, illustrating the manner in which each dustpan 18 is pivotally mounted on each end partition 12 and 12a;

Figure 10 is an enlarged partial sectional view taken adjacent the exterior face of end partition 12, showing the construction of bearing portion 10a of hollow pindle 10, and the manner in which the bearing portion 10a is retained in recess 25 by a retaining strap 20;

Figure 11 is an enlarged partial plan view showing the manner in which spring 8 is secured to actuating plunger 7 and spring lever 11.

The broad principles of the present invention, as illustrated in the above designated drawings, are applied to a sweeper employing a conventional dustpan spring arrangement, wherein the ends of an inverted loop spring are secured to opposite dustpans. Ordinarily two such springs

are employed one adjacent the inner face of each end partition 12 and 12a. However, in the accompanying drawings, only one such spring is shown. Normally, these springs act to bias the dustpans to their closed positions. Thus, to dump the dustpans, it is customary to raise the loop of one of the dustpan springs, and to thereby pull the dustpans to an open or dumping position.

To raise the spring loop, it has been customary 10 to provide a dumping lever pivotally mounted on one end of the sweeper housing. One end of such lever has been attached to the spring loop, while the other end has been arranged so that it could be depressed by an operator.

15 As adverted to in my aforesaid copending application, this arrangement has been found to be objectionable in that the operator is required to hold the sweeper handle and steady the sweeper housing while actuating the dumping lever.

20 Limitations, controlled by the practical width of the sweeper casings, have not allowed a satisfactory ratio for the casing carried dumping lever. Accordingly, considerable pressure has been required to raise one spring loop against 25 the biasing action of the other spring.

30 A more serious objection has been encountered as a result of the clumsy and awkward operation of the casing carried dumping lever. Accordingly, since the success of carpet sweepers depends upon frequent and regular cleaning of the dustpans, the actuating mechanism for opening and closing the dustpans has become a problem of serious concern.

35 To overcome these and lesser objections, not specifically enumerated, I have arranged the dustpan actuating lever so that it is carried by the operating handle of the sweeper.

This arrangement enables the operator to, in effect, ignore the relative position of the casing 40 with respect to the operating handle, when actuating the dustpan dump lever carried by the operating handle.

45 Placing the actuating lever on the operating handle, has made possible a very desirable lever ratio, and a definitely improved finger grip, so that the lever may be actuated either by pulling or pushing, according to the preference of the operator.

50 Thus, my invention provides for simple and easy operation of the dustpan actuating lever, and in a manner that is more graceful and natural for the operator.

55 Referring now in detail to the accompanying drawings, it will be observed that the sweeper casing 1 includes end partitions 12 and 12a.

60 In Figure 1 it will be observed that the sweeper casing 1 is provided with a one-piece metal cover that is equipped with a rubber band portion 1b, which hand portion protects the furniture etc. from scratches and excessive abrasions. Within the metal cover, end partitions 12 and 12a are placed as shown in Figure 6, which partitions are connected by side members 19, 19 as illustrated 65 in Figure 2.

65 In either Figure 1, 2 or 3, it will be observed that the operating handle 4 is secured through a ferrule connection 5 to a hollow arm 6, which arm projects through an aperture in the top of a 70 sweeper casing and is rigidly secured to a hollow shaft 10 extending transversely of the sweeper casing.

75 In Figure 6 the rigid connection of hollow arm 6 to the hollow shaft 10 is clearly shown. In the herein illustrated embodiment of my invention,

I have preferably fashioned the hollow shaft 10 from sheet stock.

Figures 7, 8 and 10 show the relative sectional shape at the corresponding points transversely along the hollow shaft 10. At the center of shaft 5 10, opposite the rigid connection of arm 6 thereto, the sectional shape of shaft 10 substantially corresponds with that of the bearing portions 10a shown in Figure 10.

Referring again to Figure 6 it will be observed 10 that fabricated brush combs 22 are rigidly secured to shaft 10, and are constructed so as to close the gap formed along the lower side of the shaft, shown in Figure 8.

In Figures 6 and 10 the pivotal mounting of 15 shaft 10 in the end partitions 12 and 12a is clearly illustrated. It will be noted that each partition is provided with a rounded recess 25 receiving the corresponding bearing portions 10a of shaft 10, and that each partition is further 20 provided with a rectangular recess receiving a retaining strap 20, which strap is secured thereto by brads 24, or their equivalent.

Each remote end of shaft 10 is provided with a depending arm 10b that carries a pin 9. The 25 pins 9, 9 do not form a part of the dustpan operating mechanism, as they are used in connection with a pressure regulating device for the wheels carried by the corresponding partition. In Figure 2 the general shape of the arms 10b is illustrated.

As adverted to at the outset, hollow arm 6 is rigidly secured to shaft 10. In the herein illustrated embodiment, this connection is effected by providing shaft 10 with an aperture through 35 which the arm 6 passes. To provide a very rigid and substantial connection of arm 6 to shaft 10, the arm 6 is bifurcated. The bifurcations are bent at 90 degrees to arm 6 and welded to the inner face of hollow shaft 10. Accordingly, the 40 aforesaid construction provides an uninterrupted communication between the hollow portion 6b of arm 6, and the hollow portion of shaft 10. This construction is utilized in the operation of the dustpan actuating mechanism, as will be 45 described in detail hereinafter.

In Figures 6 and 2 it will be noted that a brush 14, of the conventional type, is pivotally supported transversely between the end partitions 12 and 12a by bearing pins 23, 23. Similarly, a 50 pair of dustpans 10, 10 are pivotally mounted transversely between the end partitions, in the manner illustrated in Fig. 9. The relation between the dustpans, brush and shaft pivots 10a is particularly shown in Fig. 2.

55 Referring more in detail to Figure 2, it will be observed that the dustpans are connected by a wire spring 16 having an upwardly extending loop. As hereinbefore mentioned, two such springs are ordinarily used, one adjacent the inner face of each partition 12 and 12a, and each spring is arranged to normally bias the dustpans to their closed positions. To simplify the drawings, only one such spring is shown in the accompanying drawings, and it is to be understood 60 that my invention will perform equally well, insofar as dustpan dumping is concerned, whether one or both springs are used.

65 A spring lever 11 is pivotally mounted on the end partition 12 by a bearing pin 13, as illustrated in Figure 4. The free end of spring lever 11 is provided with an upstanding projection, which projection engages the uppermost portion of the inverted spring loop.

70 As illustrated in Figures 3, 6 and 11, a chain 75

8, or other flexible connecting member, permanently interconnects an actuating plunger 7 with in the hollow arm 6, and the upstanding projection on spring lever 11.

5 In the accompanying drawings, a conventional plumbing waste stopper chain 8 is shown, and the chain is secured to spring lever 11 by passing the upstanding projection through one of its rectangular openings. In order to assure that the 10 spring 16 remains connected to the spring lever 11, a small loop is fashioned in the uppermost portion of the inverted spring loop through which the upstanding projection likewise passes.

Referring in particular to Figure 6, it will be 15 observed that one of the bifurcations of the hollow arm 6 is formed with a suitable curvature so as to provide a satisfactory guide and bearing for chain 8, where the chain passes from the hollow arm 6 into the hollow shaft 10. Similarly, the 20 hollow shaft 13, adjacent partition 12, is provided with a flared spring guide 21, which guide is rigidly secured to the lower face of hollow shaft 10 so as to provide a satisfactory guide and bearing for chain 8 where it passes from hollow 25 shaft 10 to connect spring arm 11.

From the description thus far presented, it will be obvious that an upward movement of the actuating plunger 7 will pull chain 8, which, in turn, will raise the loop of spring 16, and thereby move simultaneously the dustpans 18, 18 30 to open or dumping position.

To provide the most satisfactory operation of the actuating plunger 7, an actuating lever 3 is pivotally secured to hollow arm 6 by a 35 suitable bearing pin 2a. The construction of the bearing pin is particularly shown in Figure 5.

In Figures 1 and 2 the relative position of the 40 operating lever 3 with respect to the detachable operating handle 4, is shown. At this time attention is directed to the threaded portion of arm 6, and the associated adjusting nuts 6c. Inspection of Figures 2 and 3 will reveal that the actuating lever 3 is pivotally mounted on a 45 ring member 2, which ring member surrounds the threaded portion of hollow arm 6. In this respect it is to be understood that the ring member 2 is freely slidable along the threaded portion of arm 6. Thus, the adjusting nuts 6c serve to rigidly secure the ring member 2, to 50 hollow arm 6 in its proper operating location.

Obviously, variation in the length of chains 8 is encountered in production. Accordingly, adjusting nuts 6c are employed to compensate for such variations in chain lengths. Thus, for 55 longer chains, the ring member 2 is moved upwardly along arm 6, while, for shorter chains, the ring member 2 is lowered.

Figure 3 is an enlarged sectional view showing the actuating lever 3. Therefore, operation of the actuating lever can be clearly understood by referring to Figure 3.

It will be noted that the upper end of actuating lever 3 is fashioned with a suitable finger grip, while the lower end is provided with a suitable cam that projects through a slot 6c in hollow arm 6 into the interior thereof.

As hereinbefore described, an actuating plunger 7 is arranged within the hollow arm 6. In 70 Figure 11 the construction of the actuating plunger 7 is shown. Thus, it will be apparent, from an inspection of Figures 3 and 11, that the cam portion of actuating lever 3 operates in the milled slot 7b of the actuating plunger 7.

75 From the foregoing description it will be ap-

parent that operation of the dustpans is accomplished by moving the finger grip outwardly from the hollow arm 6, which moving may be effected either by pulling or pushing actuating lever 3, according to the preference of the operator.

Therefore, with the actuating lever 3 in the position shown in Figure 3, spring 16 biases the dustpans 18, 18 to their closed or operating positions. Moving the finger grip outwardly, as aforesaid, raises actuating plunger 7, which, in turn, pulls chain 8 and accordingly raises the associated spring 16. Raising the latter mentioned spring opens the dustpans against the biasing action of the other spring. At this time 15 reference is made to the fact that in order to provide sufficient opening of dustpans 18, 18, it is not necessary to raise the free ends of spring 16 above the pivotal center of dustpan pivots 17, 17. Accordingly, the spring 16 is always positioned to bias the dustpans 18, 18 toward their closed positions. Therefore, closing of the dustpans is accomplished by the biasing action of spring 16, when the lever 3 is restored 20 to its normal position.

In Figure 2 the usual wheels of the carpet sweeper are shown. While the wheels are not shown in Figure 6, it is to be understood that such wheels are ordinarily located adjacent the respective outside faces of end partitions 12 and 30 12a. Accordingly, in the present embodiment of my invention, the wheels are covered by the one-piece cover.

In order to provide sufficient angular movement for the operating handle 4, a slot is formed 35 in the top of the sweeper casing. Thus, to eliminate dust leakage from the slot, I have provided a trim plate 1a having a depending well and a suitable smaller slot for straddling the hollow shaft 10. The construction and arrangement of the trim plate is particularly shown in Figures 1 and 6.

Thus, it will be apparent that my invention has provided a very efficient and conveniently operable dustpan dumping mechanism that can 40 be operated independently of the relative positions of the sweeper casing and operating handle, which mechanism requires the minimum handling of parts of the sweeper by the operator while actuating the dumping mechanism.

Having thus described my invention, I claim:

1. A carpet sweeper comprising, in combination, a dust compartment having a top and end walls, said top having a centrally disposed opening therein; dustpans within the said compartment pivotally mounted between the said end walls; a spring within the said dust compartment located adjacent the inner surface of one end wall thereof, and extending between the 55 pans for normally biasing the said pans to their closed positions, the said spring having an upwardly extending loop, which is raised to dump the said dustpans; a hollow shaft pivotally mounted within the said dust compartment, having one of its ends extending adjacent to and above the said upwardly extending loop; a hollow stub handle fixedly secured to the said shaft and projecting through the said opening; the bore of the hollow stub handle communicating with the bore of the hollow shaft; a 60 dumping lever pivotally mounted on the said stub handle; and a flexible cable operating within the bores of the stub handle and shaft, operatively connecting the dumping lever and the 65 upwardly extending loop, for raising the 70

75

said loop to dump the pans when the lever is actuated.

2. A carpet sweeper comprising, in combination, a dust compartment having a top member and end walls, the said top having an opening therethrough communicating with the interior of the said compartment; a dustpan within the said compartment pivotally mounted between the said end walls; a hollow stub handle projecting through the said opening and pivotally mounted to the carpet sweeper within the said dust compartment; a dumping lever pivotally mounted on the said handle; a spring within the dust compartment normally biasing the said pan to its closed position, the said spring having an upwardly extending loop, which is raised to dump the said dustpan; and a flexible cable extending from within the dust compartment through the bore of the handle and operatively connecting the said upwardly extending loop and said lever, for raising the said loop to dump the said pan, when the said lever is actuated.

3. A dustpan actuating mechanism for a carpet sweeper, comprising, a sweeper casing, the said casing having an opening in the top member thereof communicating with the interior of the said casing; a hollow stub handle pivotally mounted within the casing projecting outwardly through the said opening and having an operating handle fixedly secured to the outer end thereof, the said stub handle having a longitudinal slot formed therein adjacent its outer end; a plunger slidably mounted within the bore of the said stub handle and longitudinally movable therein; a lever pivotally mounted on the said stub handle adjacent the said longitudinal slot, the said lever having a projection extending through the longitudinal slot and operatively engaging the said plunger, for moving the said plunger longitudinally upwardly when the lever is actuated; a dustpan pivotally mounted within the said casing; and means extending from within the casing through the bore of the said stub handle, and operatively connecting the said plunger and said dustpan for moving the dustpan to an open position, when the said plunger is moved longitudinally upwardly by actuation of the said lever.

4. A carpet sweeper comprising, in combination, a dust compartment having a top member and side walls, said top having a centrally disposed opening therein; dust pans pivotally mounted within the said compartment; a spring within the said dust compartment located adjacent the inner face of one side wall thereof, and operatively associated with the pans for normally biasing the said pans to their closed positions, the said spring having an upwardly extending loop which is raised to dump the said pans; a hollow shaft pivotally mounted within the said dust compartment, and having one of its ends extending substantially adjacent to and above the said upwardly extending loop; a hollow handle fixedly secured to the said shaft and projecting through the said opening, the bore of the hollow handle communicating with the bore of the hollow shaft; an actuating member movably mounted on the said handle; and means operating within the bores of the said handle and said shaft, and operatively connecting the said actuating member the said upwardly extending loop, for raising the said loop to dump the pans, when the said member is actuated.

5. A carpet sweeper comprising, in combination, a dust compartment having a top member

and side walls, the said top having an opening therethrough communicating with the interior of the said compartment; a dustpan pivotally mounted within the said compartment; a hollow handle projecting through the said opening, and pivotally secured to the carpet sweeper within the said dust compartment; an actuating member movably mounted on the said handle; a spring within the said dust compartment operatively associated with the said pan and normally biasing the said pan to its closed position, the said spring having an upwardly extending loop which is raised to dump the said dustpan; and means extending from within the said dust compartment through the bore of the said handle, and operatively connecting the said upwardly extending loop and the said actuating member, for raising the said loop to dump the said pan, when the said member is actuated.

6. A carpet sweeper comprising, in combination, a dust compartment having a top member and side walls, the said top having an opening therethrough communicating with the interior of the dust compartment; a dustpan pivotally mounted within the said compartment; a spring within the said dust compartment located adjacent the inner face of one side wall thereof, and operatively associated with the pan for normally biasing the same to a closed position, the said spring having an upwardly extending loop which is raised to dump the said dustpan; a lever pivotally mounted adjacent the inner face of the said one side wall, and having its free end operatively engaging the upwardly extending loop of the said spring; a hollow shaft pivotally mounted within the said dust compartment, and having one of its ends extending substantially adjacent to and above the said lever; a hollow handle fixedly secured to the said shaft and projecting through the said opening, the bore of the hollow handle communicating with the bore of the hollow shaft; an actuating member mounted on the said handle; and means operating within the bores of the said handle and said shaft, and operatively connecting the said actuating member and the said lever, for actuating the said lever to raise the loop of the said spring and thus move the said pan to a dumping position, when the said member is actuated.

7. A carpet sweeper comprising, in combination, a dust compartment having a top member and side walls, the said top having an opening therethrough communicating with the interior of the said compartment; a dustpan pivotally mounted within the said dust compartment; means operatively associated with the said pan, for biasing the same to a closed position; a hollow handle projecting through the said opening, and pivotally secured to the carpet sweeper within the said dust compartment; an actuating member movably mounted on the said handle; and means extending from within the said dust compartment through the bore of the said handle, and operatively connecting the said pan and the said actuating member, for moving the said pan to a dumping position, when the said member is actuated.

8. A carpet sweeper comprising, in combination, a dust compartment having a top member and side walls, the said top having an opening therethrough communicating with the interior of the said compartment; dustpans pivotally mounted within the said dust compartment; dumping means operatively associated with the

5 said pans, for moving the pans to a dumping position, when the said dumping means is actuated; a hollow handle projecting through the said opening, and pivotally secured to the said sweeper within the said dust compartment; an actuating member movably mounted on the said handle; and means extending from within the said compartment through the bore of the said handle, and operatively connecting the said dumping 10 means and the said actuating member, for actuating the said dumping means, and thus moving the said pans to a dumping position, when the said member is actuated.

10 9. A carpet sweeper comprising, in combination, a dust compartment having a top member and side walls, the said top having an opening therethrough communicating with the interior of the said compartment; a dustpan disposed within the said compartment and pivotally secured to the said sweeper; a hollow handle projecting through the said opening and pivotally secured to the said sweeper within the said compartment; an actuating plunger slidably mounted within the bore of the said handle and longitudinally movable therein; a spring within the 15 said compartment operatively associated with the said pan and normally biasing the same to a closed position, the said spring having an upwardly extending loop that is raised to dump the said pan; actuating means slidably mounted within the bore of the said handle for longitudinal movement therein, and extending longitudinally through the bore of the said handle into the interior of the said dust compartment and operatively connecting the said loop for raising the said loop to 20 dump the said pan, when the said actuating means is moved longitudinally upwardly in the bore of the said handle; and an actuating member movably mounted on the said handle, and operatively engaging the said actuating means, 25 for moving the said means longitudinally upwardly, when the said member is actuated.

longitudinally upwardly; and an actuating member movably mounted on the said handle, and operatively engaging the said plunger, for moving the said plunger longitudinally upwardly, when the said member is actuated.

5

10 10. A carpet sweeper comprising, in combination, a dust compartment having a top member and side walls, the said top having an opening therethrough communicating with the interior of the said compartment; a dustpan disposed within the said compartment, and pivotally secured to the said sweeper; a hollow handle projecting through the said opening and pivotally secured to the said sweeper within the said compartment; a spring within the said compartment 15 operatively associated with the said pan, and normally biasing the same to a closed position, the said spring having an upwardly extending loop that is raised to dump the said pan; actuating means slidably mounted within the bore of the said handle for longitudinal movement therein, and extending longitudinally through the bore of the said handle into the interior of the said dust compartment and operatively connecting the said loop for raising the said loop to 20 dump the said pan, when the said actuating means is moved longitudinally upwardly in the bore of the said handle; and an actuating member movably mounted on the said handle, and operatively engaging the said actuating means, 25 for moving the said means longitudinally upwardly, when the said member is actuated.

NORMAN W. CUMMINS.
